UNITED STATES PATENT OFFICE.

ALLEN M. ROSSMAN, OF WILMETTE, ILLINOIS.

INTERNAL-COMBUSTION ENGINE.

1,306,777.

Specification of Letters Patent. Patented June 17, 1919.

Application filed June 8, 1917. Serial No. 173,456.

To all whom it may concern:

Be it known that I, ALLEN M. ROSSMAN, a citizen of the United States, residing at Wilmette, in the county of Cook and State 5 of Illinois, have invented a certain new and useful Improvement in Internal-Combustion Engines, of which the following is a full, clear, concise, and exact description, reference being had to the accompanying 10 drawings, forming a part of this specification.

My invention relates to internal combustion engines of the two cycle type, and particularly to that class of two cycle engines 15 wherein two pistons and two cylinders are utilized for each power unit, one piston and cylinder operating as a compressor or pumping mechanism and the other cylinder and piston as the power mechanism, the 20 former being arranged to feed fuel to the latter. In this type of engine the cylinders may be positioned adjacent one another, or may be made of the differential type in which a differential piston is mounted in a differential cylinder, and in which one portion of 25 the cylinder serves as the power chamber and the other the pumping chamber. The compression cylinder of the engine connects with a combustion chamber in turn arranged 30 to communicate with the power or working cylinder, the operation of the engine being such that the compression cylinder is adapted to take in a fresh charge of combustible mixture and to compress it and force it into 35 the combustion chamber wherein combustion takes place. The gases are then ignited in the combustion chamber and are permitted to pass out of the chamber into the working cylinder where the power of the expanding 40 gases is utilized to act upon the working piston.

It is one of the objects of the present invention to provide means for completely scavenging the combustion chamber after 45 each ignition of the gases therein so that when a new charge is forced into the combustion chamber it will not be contaminated by partly burned gases left from the previous charge.

It is a further object of the present invention to scavenge the combustion chamber mechanically, that is, by means of a 50 movable wall as distinguished from the method of scavenging by a draft of air through the combustion chamber, the latter 55 method being ineffective and unreliable,

A further object of the invention is the provision of improved valve mechanism for affording communication between the compression cylinder and the combustion chamber and between the combustion chamber and the working cylinder, the valve mechanism being controlled and actuated directly by the crank shaft of the engine.

These and other features of my invention 65 will be pointed out in detail in connection with the accompanying drawings wherein the mechanism of my invention is illustrated rather diagrammatically, and in which—

Figure 1 is a vertical cross sectional view 70 of an engine embodying the preferred form of my invention;

Fig. 2 is a view similar to Fig. 1 showing the crank shaft of the engine rotated 180° from the position shown in Fig. 1; 75

Fig. 3 is a vertical cross sectional view taken along the line 3—3 of Fig. 1 looking in the direction indicated by the arrows;

Fig. 4 is a vertical cross sectional view of 80 an engine showing a modified form of valve mechanism;

Fig. 5 is a view similar to Fig. 4 showing the crank shaft moved to a position 180° from that shown in Fig. 4; and

Fig. 6 is a vertical cross sectional view 85 taken along the line 6—6 of Fig. 4 looking in the direction indicated by the arrows.

Similar characters of reference refer to similar parts throughout the several views.

Referring first to the preferred form of 90 my invention shown in Figs. 1, 2, and 3, 7 designates the engine casing comprising a compression cylinder 8, a combustion chamber 9, and a power or working cylinder 10. Attached to the casing 7 at 11 is the crank 95 casing 12 provided with the bearings 13—13 for journaling the crank shaft 14. The crank shaft 14 has the two crank arms 15 and 16, the former of which is connected with the compression piston 17 through the 100 pitman rod 18 and the latter connected with the power piston 19 through the pitman rod 20. The cranks 15 and 16 are preferably of the same radius and are in approximate alinement with each other. The crank shaft 105 is provided with a third crank arm at 21 which is disposed substantially 180° away from the cranks 15 and 16 and is connected with a piston 22 reciprocably mounted in the combustion chamber and connected with the crank arm 21 by the pitman rod 23. The side wall of the combustion chamber 9 is

formed by a sleeve 24 which has its upper end fitting between the engine casing 7 and a plug 25 secured to the casing at 26. The lower end of the sleeve 24 is connected 5 through the arm 27 with a crank arm 28 located substantially 90° away from the crank arms 15, 16, and 21.

Arranged to provide communication between the compression cylinder 8 and the 10 combustion chamber 9 is a port 29 positioned at the head of the compression cylinder. A similar port is provided at 30 at the head of the power cylinder and is arranged to provide communication between the combustion 15 chamber and the power cylinder. Extending downwardly through the plug 25 is an inlet port 31' adapted to communicate with the port 31 which has free communication with the upper end of the compression 20 cylinder. The plug 25 also contains the exhaust port 32 adapted to communicate with the port 33 communicating with the head of the power cylinder. The sleeve 24 is provided with the three ports shown at 34, 35, 25 and 36, each of which is arranged to register with one of the ports provided in the engine casing to effect certain communication between the cylinders and the combustion chamber, as will be described presently. The 30 plug 25 also carries a spark plug 37, which serves to ignite the charge in the combustion chamber. The intake port 31' is in communication with any suitable carburetor so that upon operation of the engine a combustible mixture is introduced into the cylinders.

The operation of the device is as follows: As the crank 14 rotates in the direction indicated by the arrow in Fig. 3 the pistons 17 and 19 are moved downwardly, as is the 40 sleeve valve 24. At the same time the piston 22 is moved toward the head of the combustion chamber. As the sleeve 24 moves downwardly its port 35 is brought into communication with the ports 31' and 31 so that a 45 fresh charge of fuel is introduced into the cylinder 8 upon downward movement of the piston 17. It will be observed that when the crank 15 has been moved 90° about its axis the port 35 will assume a position such that 50 the inlet ports 31' and 31 are in free communication with one another. When the crank 15 has been rotated 180° the port 35 is again moved upwardly to the position shown in Fig. 1. Fig. 2 shows the crank advanced 55 180° and the sleeve 24 in the position which it occupies with respect to the crank at that time. As the piston 17 moves upwardly the sleeve 24 is also moved upwardly so that its port 34 registers with the port 29 and provides 60 free communication between the compression cylinder 8 and the combustion chamber 9. As the pistons 17 and 19 move upwardly the piston 22 moves downwardly so that the gases taken in by the cylinder 8 65 are forced into the combustion chamber.

When the piston 17 again reaches the position shown in Fig. 1 the sleeve 24 takes the position shown in Fig. 1 so that communication between the combustion chamber and the compression cylinder is prevented. The 70 charge is then ignited in the combustion chamber by the spark plug 37 and as the crank shaft continues to rotate the sleeve 24 is again moved downwardly so that its port 36 registers with the port 30 and permits 75 the expanding gases to pass from the combustion chamber into the power cylinder 10 and act upon the power piston 19. As the pistons 17 and 19 move downwardly the piston 17 takes in a fresh charge and the 80 piston 22 moves clear to the head of the combustion chamber 9 so that it completely scavenges the gases which had previously been ignited and forces the gases into the power cylinder. At the end of the power 85 stroke the pistons assume the position shown in Fig. 2 and upon their return upward movement the sleeve 24 is again moved upwardly so as to bring its port 34 in alignment with the port 29 and its port 36 in 90 alignment with the exhaust ports 32 and 33. The piston 19 then completely scavenges the cylinder 10 and on the next down stroke receives a fresh charge of expanding gases 95 from the combustion chamber. 95

It will be seen from the above description that I provide a single sleeve valve controlled directly from the crank shaft for regulating communication between the cylinders and the combustion chamber and that 100 I provide means whereby the combustion chamber may be scavenged completely after the ignition of the gases therein so that premature ignition of a fresh charge of gases in the chamber is entirely eliminated. 105

In Figs. 4, 5, and 6, the engine comprises the compression cylinder 38, the combustion chamber 39, and the power cylinder 40. The upper end of the compression cylinder is provided with the two ports 41 and 42, the former serving as an inlet port and the latter as a means for providing communication between the compression cylinder and the combustion chamber. The upper end of the power cylinder contains the two ports 43 and 44, the former for permitting the expanding gases in the combustion chamber to pass into the power cylinder and the latter for exhausting the gases from the power cylinder. The pistons 45 and 46 are connected with 110 the crank arms 47 and 48 respectively of the crank 49, the crank arms being preferably of like radius and positioned in substantial alignment with each other. Reciprocably mounted within the compression cylinder 38 115 is a sleeve 49' connected with the crank arm 50 by the rod 51. The power cylinder 40 contains the sleeve 52 connected with the crank arm 53 by the rod 54. The crank arms 50 and 53 are located substantially 90° away 120 125

from the crank arms 47 and 48 and are positioned approximately 180° away from each other, as most clearly shown in Fig. 6. A fifth crank arm is provided at 55 positioned substantially 180° away from the crank arms 47 and 48 and is connected with the piston 56 reciprocably mounted in the combustion chamber 39. The upper end of the sleeve 49' contains the two ports 57 and 58 and the upper end of the sleeve 52 contains the two ports 59 and 60.

Assuming the combustion chamber 39 to contain a charge of combustible gases and that the gases are ignited by the spark plug illustrated, the operation of the engine is as follows: As the crank 49 rotates in the direction indicated by the arrow in Fig. 6 the pistons 45 and 46 are moved downwardly, the piston 56, upwardly, the sleeve 49' upwardly, and the sleeve 52 downwardly, whereby the port 57 of the sleeve 49 registers with the port 41 and the port 59 of the sleeve 52 registers with the port 43. The expanding gases in the combustion chamber are thus permitted to enter the power cylinder and act upon the piston 46. At the same time a fresh charge of combustible gas is admitted to the compression cylinder 38 due to the downward movement of the piston 45. When the pistons 45 and 46 reach the end of their downward stroke, as shown in Fig. 5, the sleeves 49' and 52 take the position shown in Fig. 5 and the piston 56 occupies a position at the head of the combustion chamber, the movement of the piston 56 to this position serving to remove the burned gases from the combustion chamber entirely. As the pistons 45 and 46 move upwardly and the piston 56 downwardly the sleeve 49' is moved downwardly and the sleeve 52 upwardly so that the port 58 of the sleeve 49' registers with the port 42 and the port 60 of the sleeve 52 registers with the port 44. The piston 45 then forces the fresh charge into the combustion chamber and the piston 46 forces the burned and inert gases out through the exhaust port 44. When the pistons 45 and 46 reach their uppermost position the sleeve valves 49' and 52 again assume the positions shown in Figs. 4 and 5 and the operation just described is repeated.

Although I have described and illustrated my invention as applied to an engine in which a combustible mixture is compressed in the compression chamber and forced from the chamber into a combustion chamber, it will readily be apparent that modifications of this arrangement may be made without departing from the spirit and scope of the invention.

Having thus described my invention what I claim as new and desire to secure by Letters Patent of the United States is:

1. In an internal combustion engine, the combination of a compression cylinder, a

power cylinder, pistons in said cylinders, a combustion chamber, valve mechanism for providing communication between the cylinders and the combustion chamber, a movable wall in the combustion chamber for mechanically scavenging the gases therein, a crank shaft connected with said pistons and movable wall, and means for igniting a charge in the combustion chamber when the movable wall reaches its outermost position in the combustion chamber.

2. In an internal combustion engine the combination of a compression cylinder, a power cylinder, a crank shaft, pistons in said cylinders and connected with the crank shaft, a combustion chamber, valve mechanism for providing communication between the cylinders and combustion chamber, a movable wall in the combustion chamber and connected directly with the crank shaft for mechanically scavenging the gases therein, and means for igniting a charge in the combustion chamber when the movable wall reaches its outermost position in the combustion chamber.

3. In an internal combustion engine the combination of a compressor, a power cylinder, a piston in the power cylinder, a combustion chamber arranged to communicate with the compressor and power cylinder, a movable wall in the combustion chamber for mechanically scavenging the gases therein, a crank shaft connected with said piston and movable wall, and means for igniting a charge in the combustion chamber when the movable wall reaches its outermost position in the combustion chamber.

4. An internal combustion engine comprising a compressor, a power cylinder, a crank shaft, a piston in the power cylinder and connected with the crank shaft, a combustion chamber arranged to communicate with the compressor and power cylinder, a movable wall in the combustion chamber and connected directly with the crank shaft for mechanically scavenging the gases in the combustion chamber, and means for igniting a charge in the combustion chamber when the movable wall reaches its outermost position in the combustion chamber.

5. An internal combustion engine comprising a compression cylinder, a power cylinder, a crank shaft, pistons in the cylinders and connected with the crank shaft, a combustion chamber, and a single valve unit connected directly with the crank shaft for controlling communication between the cylinders and the combustion chamber.

6. An internal combustion engine comprising a compression cylinder, a power cylinder, a crank shaft, pistons in the cylinders and connected with the crank shaft, a combustion chamber, and a single valve unit connected directly with the crank shaft for

controlling communication between the cylinders and the combustion chamber and between the cylinders and the atmosphere.

7. In an internal combustion engine the combination of a compression cylinder, a power cylinder, a crank shaft, pistons in the cylinders and connected with the crank shaft, a combustion chamber, and a single sleeve valve for controlling communication between the cylinders and the combustion chamber.

8. In an internal combustion engine the combination of a compression cylinder, a power cylinder, a crank shaft, pistons in the cylinders and connected with the crank shaft, a combustion chamber, and a single sleeve valve for controlling communication between the cylinders and the combustion chamber and between the cylinders and the atmosphere.

9. In an internal combustion engine the combination of a compression cylinder, a power cylinder, a crank shaft, pistons in the cylinders and connected with the crank shaft, a combustion chamber, and a single sleeve valve connected directly with the crank shaft for controlling communication between the cylinders and the combustion chamber.

10. In an internal combustion engine the combination of a compression cylinder, a power cylinder, a crank shaft, pistons in the cylinder and connected with the crank shaft, a combustion chamber, and a single sleeve valve connected directly with the crank shaft for controlling communication between the cylinders and the combustion chamber and between the cylinders and the atmosphere.

11. An internal combustion engine comprising a compression cylinder, a power cylinder, a crank shaft, pistons in the cylinders and connected with the crank shaft, a combustion chamber arranged to

communicate with said cylinders, and a piston in the combustion chamber and connected with the crank shaft, at a point substantially 180° away from the connection between the compression and power pistons and the shaft, for mechanically scavenging the gases in the combustion chamber.

12. An internal combustion engine comprising a compression cylinder, a power cylinder, a crank shaft, pistons in the cylinders and connected with the crank shaft, a combustion chamber, a single valve unit for providing communication between the combustion chamber and the cylinders and between the cylinders and the atmosphere, and a piston in the combustion chamber and connected with the crank shaft, at a point substantially 180° away from the connection between the compression and power pistons and the shaft, for mechanically scavenging the gases in the combustion chamber.

13. In an internal combustion engine the combination of a compression cylinder, a power cylinder, a crank shaft, pistons in the cylinders and connected with the crank shaft, a combustion chamber, a single sleeve valve in the combustion chamber and connected directly to the crank shaft for providing communication between the combustion chamber and the cylinders and between the cylinders and the atmosphere, and a piston in the combustion chamber connected with the crank shaft, at a point substantially 180° away from the connection between the compression and power pistons and the shaft, for mechanically scavenging the gases in the combustion chamber.

In witness whereof I hereunto subscribe my name this 31st day of May, A. D. 1917.

ALLEN M. ROSSMAN.
